METHOD AND MACHINE FOR PRODUCING TAPERED GEARS

Application filed February 28, 1927. Serial No. 171,608.

The present invention relates to tapered gears, both bevel and hypoid, and to a method and machine for producing such gears.

This invention involves a novel method 5 of producing tapered gears, wherein the usual relative motion between tool and blank about the axis of a basic crown gear is supplanted by a straight line relative motion between the two bodies, as though, broadly, 10 the gears were being generated from a basic member performing a straight line motion.

The present invention permits of producing tapered gears upon machines of simple construction in which the carrier, upon which 15 the tool or blank is mounted, performs a straight line motion instead of an oscillatory or rotary motion as in the usual type of tapered gear generating machines.

The present invention permits, also, of 20 employing a straight line motion in the production of tapered gears without affecting appreciably the shape of the teeth cut.

This invention provides, further, a method 25 for cutting tapered gears which permits of cutting both members of a pair, two side faces simultaneously without bias bearing, that is, without a tooth surface contact which extends diagonally across the faces of the teeth.

30 The principles of the invention and some of its uses and embodiments are illustrated in the accompanying drawings. It will be understood, however, that this invention is not restricted to the particular embodiments 35 and uses shown, but that it is capable of such further modifications and uses as come within its scope and within the limits of the accompanying claims.

In the drawings:

40 Figures 1 and 2 are a front elevation, partly in section, and a side view, respectively, illustrating somewhat diagrammatically a machine constructed and operating according to the principles of this invention and illustrating one embodiment thereof;

45 Figure 3 is a sectional plan view of this machine;

50 Figure 4 is a diagrammatic view illustrating the preferred manner of practising

this invention in the production of one member of a curved tooth bevel pair;

Figure 5 is a corresponding view illustrating the manner in which the gear which is to mate with the gear in Figure 4 may be 55 cut; and

Figures 6 and 7 are diagrammatic views illustrating further embodiments of the invention.

Tapered gears, both bevel and hypoid, are 60 customarily generated by providing a cutter which represents a tooth or a tooth side of a basic gear, such as a crown gear, and by moving the cutter and gear blank relatively to each other as though the blank were meshing 65 with the basic gear represented by the tool. In this generating operation, the tool or blank is swung in a circular path about the axis of the basic gear.

According to the present invention, tapered gears are generated by imparting a relative straight line motion between the tool and blank instead of the customary circular motion. This straight line motion is in addition to the cutting motion of the tool and 70 the rotary motion of the blank on its axis. Gears produced with the present invention will transmit true uniform motion.

The present invention may be used advantageously, moreover, in cutting tapered gears, two tooth sides simultaneously, since 75 with the method of this invention, it is possible to cut both gears of a pair in this manner and have them run together without "bias bearing" that is, without a tooth bearing 80 which extends diagonally across the tooth surfaces.

Although a straight line motion, which 85 may be regarded as a rack motion, is employed in producing gears with the present invention, the gears produced are actually tapered gears and are of the same general structure as tapered gears produced according to prior methods, differing, hence, from 90 spur gears which are customarily generated with a straight line motion.

The principles underlying the production 95 of tapered gears according to the present invention are illustrated diagrammatically in 100

Figures 4 and 5. These figures compare specifically the method ordinarily used for producing a curved tooth bevel gear, with the process by which such a gear may be produced according to this invention. Referring first to Fig. 4, where the production of the pinion or smaller member of the pair is shown, 10 indicates the pinion blank, 11 its axis, and 12 its apex. The concentric circles 13 and 13' designate the cutter or tool which is of the rotary annular face mill type. The axis 11 of the blank is inclined to the plane of the drawing by the pitch cone angle of the blank. Hence, the plane of the drawing might be considered the pitch plane of a true crown gear whose axis is perpendicular to the plane of the drawing and passes through the pinion apex 12.

In the usual operation of producing a bevel gear from a pinion blank, such as the blank 10, the tool 13 is rotated on its axis 14 in engagement with the blank and simultaneously the tool and blank are rolled relatively to each other about the axis of the crown gear. In this rolling motion, either the tool or the blank will be swung in a circular path about the axis of the crown gear. For the sake of clearness, I have shown the tool so swung. 14 designates the position of the tool axis at the center of the cut on the tooth space 15 of the blank and 14' shows the position that the cutter would occupy say at the end of the roll, that is, when the tooth side or tooth sides being cut were fully generated. Thus, with the usual method the tool axis or the center of tooth curvature 14 has moved in a circular arc about the crown gear axis to the position 14'.

With the present invention the tool and blank instead of being swung in a circular path relatively to each other are moved relatively in a straight line direction. Thus, with the present invention during the generation of a tooth side or tooth sides, the center or axis 14 of the tool will move along the straight line 17 and will at the end of the roll assume a position such as the position 14''.

In the preferred embodiment of this invention, the tooth inclination, or spiral angle, at a mean point 18 of the tooth face, and the cutter radius are in such inter-relation that the cutter center 14 coincides with the projection of the blank apex 12 to the tooth normal 19 at the mean point 18.

The gear which is to mate with the gear cut from the blank 10 is cut, with this invention, in a similar manner to the blank 10. The gear blank is shown at 20 in Figure 5, its axis is at 21 and its apex at 22. The two concentric circles 23 and 23' designate the tool, a rotary annular face mill. In the production of the gear, as of the pinion, the tool rotates in engagement with the blank, the blank rotates on its axis and simultaneously

a relative straight line motion is imparted between the tool and blank. In this straight line motion, the tool will move to the position indicated in dotted lines at 25, and its center or axis 24 will move in to the position 24'. The tool and blank are again, preferably, so positioned relatively to each other that the tool center 24 coincides with the projection of the blank apex 22 to the tooth normal 26 at the mean point 27.

The teeth of gears cut according to the preferred embodiment of the invention, where the tools are positioned as described and as illustrated in Figures 4 and 5, will approximate in their lengthwise curvature teeth of longitudinal involute form and will have teeth of approximately constant thickness and tooth faces of approximately constant width along the entire length of the face. Like gears of involute lengthwise curvature, gears cut according to the preferred embodiment of the present invention may be provided with teeth of constant depth.

It will be seen from Figure 4, that the position 14'' assumed by the tool in the generation of gears according to this invention is displaced from the position 14' which the tool would occupy in the usual process, in a direction parallel to the tooth being cut. Inasmuch as this displacement is small and is in the direction of the tooth, it follows that the straight line motion of this invention does not affect to any appreciable extent the tooth shape of gears produced according to this invention, as compared with similar gears produced according to the usual methods.

One particular advantage of the present invention is that both members of a tapered gear pair may be cut two sides simultaneously in such manner as to run together without "bias bearing". The tool, hence, employed in cutting gears according to this invention will preferably be provided with cutting edges adapted to finish cut opposite side tooth faces of the blank. So, the tools shown in Figures 4 and 5 are shown as provided with a plurality of cutting blades 29, of which alternate blades are adapted to finish cut opposite adjacent side tooth faces of a blank. Each cutting blade might, however, be provided with a pair of finish cutting edges each of which could cut a side tooth face of the blank. In this case, the cutting blades would preferably be provided with a front rake, as described more particularly in my copending application, Serial No. 175,859, filed March 16, 1927.

An embodiment of a machine such as might be employed in producing longitudinally curved tooth bevel gears according to the principles of this invention, is illustrated somewhat diagrammatically in Figures 1 to 3. 30 designates a rotary face mill, of the

type shown in Figures 4 and 5. The tool 30 is secured to a spindle 31 which is journaled in a cutter head support 32. The cutter head support 32 is angularly adjustable on the slide 33 which in turn is mounted for sliding movement upon the upright or column 34 which is secured to the base 35 of the machine.

The blank indicated at B is mounted upon a spindle which is journaled in a support 36 which is mounted upon the base 35.

As already stated, during the cutting movement of the tool and the rotation of the blank, an additional relative straight line motion is imparted between the tool and blank in a direction inclined to a plane perpendicular to the blank axis. As an illustrative example of one means of effecting this last named motion, I have shown that the required movement may be obtained by securing to an arm 38 which is integral with the slide 33, a rack 39, which meshes with a spur pinion 40 which is connected to rotate with the blank spindle during the generating operation.

The tool 30 may be rotated on its axis by means of the motor 42, the pinion 43 which is secured to the armature shaft of the motor, and the gear 44 which is keyed to the cutter spindle 31. The motor and these gears are housed on the cutter head support 32. The tool rotates in engagement with the blank and simultaneously a feed or straight line traversing movement is imparted to the slide 33. This traversing movement may be effected, as illustrated, by rotating a screw 45 which may be driven from any suitable source of power and which engages with a nut 46 which is secured to the slide 33. The movement of the slide 33 carries the tool 30 with it and simultaneously rotates the blank spindle on its axis through the rack and pinion connection 39-40.

The machine illustrated is of the intermittent or periodic indexing type. After a tooth surface or tooth surfaces of the blank have been completely generated, the tool and blank are withdrawn relatively to each other, the blank is indexed and the tool is returned to its initial position ready to cut a new tooth face or faces of the blank. The means for withdrawing the tool and blank relatively to each other may be of any usual or suitable character, such as commonly employed upon machines for producing gears in an intermittent or periodic indexing operation. So, the actual indexing mechanism may be of any suitable or useful character, the indexing mechanism being illustrated here diagrammatically only. The pinion 40 is shown as provided with a number of holes or recesses 47, and the blank spindle has secured to it an arm 48 which carries a spring pressed plunger 49 which is adapted to engage selectively with the holes or recesses 47. During the cutting operation the gear 40 is locked

to the blank spindle by engagement of the plunger 49 with one of these holes 47, and the movement of the slide 33 produces a rotation of the gear blank through the rack and pinion connection 39-40. The gear blank is indexed by disengaging the plunger 49 from the hole 47 with which it has been engaged and by rotating the arm 48 and the blank spindle to which the arm is secured until the plunger has moved into alignment with the next hole 47 with which the plunger is then engaged. When this operation has been performed, another tooth face of the blank will be presented to the tool for operation upon and another tooth face or tooth faces of the blank may be generated.

A single angular adjustment has been shown. It will be understood, however, that the machine will be provided with any usual or necessary adjustments for positioning the tool and blank in proper position. It will be understood, also, that the relative straight line motion, new with this invention, may be obtained by any other suitable means and is not restricted to the rack and pinion connection shown.

While the machine illustrated is of the intermittent indexing type, it will be understood that the invention may be practiced also in a hobbing or continuous cutting operation and that the tool used may be either of the face mill type so constructed that successive blades or successive groups of blades engage successive tooth faces of the blank, or a hob of the worm type in which the cutting edges are arranged in a thread.

The tool 30 shown is provided with cutting edges which are of circular arc profile, and will sweep out spherical surfaces of revolution. The centers of the inside and outside cutting edges of the tool will preferably be located upon the tool axis. However, the invention is not restricted to use with cutters of circular arc profile, since tools of straight profile or any other desired curvature may be used. In Figures 6 and 7 straight or conical cutters 50 and 51 are shown.

The cutter may be positioned so that its axis is perpendicular to the pitch plane, that is, to the plane tangent to the pitch surface of the blank, or so that its axis is inclined to this plane. In Figure 6, the axis 52 of the cutter 50 is shown perpendicular to the pitch plane 53. The blank is indicated at 54, its axis at 55 and its apex at 56. This setting of the cutter is used especially when the pitch of the blank is small as compared with the cutter radius. The normal radii 57 and 58 of the outside and inside cutting edges of the tool 50 are of different lengths, the outside radius being the larger. This difference is oftentimes desirable to avoid under-cutting, but it should be very small.

When it is desired to secure cutting sur-

faces of more nearly equal radii on the inside and outside cutting edges, the tool will preferably be tilted so that its axis is inclined at an angle other than a right angle to the pitch plane. This position of the cutter is shown in Figures 1, 2 and 3 and also in Figure 7. In Figure 7, the cutter has straight profiled cutting edges. Its axis 59 is shown inclined at an angle other than a right angle to the pitch plane 60. 61 designates the blank, 62 its axis and 63 its apex. The normal radii 64 and 65 of a tool positioned such as shown in Figure 7 may be less different than the normal radii 57 and 58 of a tool positioned such as shown in Figure 6.

Curved tooth gears may be cut according to this invention, moreover, with planing tools, where the planing tools move in circular arc paths. Such tools will be positioned, preferably, according to the principles set forth with reference to the positioning of the rotary annular face mills shown. Curved tooth tapered gears may be cut, also, with the present invention by the use of planing tools where the gear blank is given a continuous indexing motion, that is, where the planing tools cut upon a different tooth face of the blank on each stroke.

The calculations by which the various dimensions of the gear and cutter may be arrived at are based upon the same considerations as underlie the production of bevel gears two side faces simultaneously from offset crown gears, as described in my copending application, Serial No. 171,606, filed February 28, 1927. A mean point of contact between the tool and blank is assumed and the calculations are based upon the positions which a point on the tooth surface directly above or below this mean point of contact assumes before it becomes a point of contact between the tool and blank.

As can be demonstrated, and as is clearly disclosed in my copending application last mentioned, the relationship between the spiral angles of the offset crown gear to which the blank is to be generated conjugate and the spiral angle of the blank, the cutter radius, and the respective cone distances of crown gear and blank may be determined as follows:

$$\frac{A \cos h}{A_s \cos h_s} \left[2 - \frac{\tan h_s}{\tan h} \right] = 1 - \frac{A}{r} \sinh \left(1 - \frac{\tanh h_s}{\tanh h} \right)^2,$$

where A is the cone distance of the gear to be cut, A_s is the cone distance of the crown gear to which it is generated conjugate, h is the spiral angle of the gear to be cut, h_s is the spiral angle of the crown gear and r is the cutter radius, the radius of tooth curvature. In the present case, the center of the generating crown gear is at infinity. In other words, basic racks are used instead of basic crown gears. Then A_s equals ∞ .

Whence:

$$1 - \frac{A}{r} \sin h \left[1 - \frac{\tan h_s}{\tan h} \right]^2 = 0$$

and:

$$\left[1 - \frac{\tan h_s}{\tan h} \right] = \pm \sqrt{\frac{r}{A \sin h}}.$$

In this equation h_s indicates the inclination of the straight feed or straight line movement of the basic rack to a normal to the tooth surface to be produced at the mean point. In the preferred embodiment shown in the drawings, h_s equals zero and the straight line movement is in the direction of the normal.

While it is considered preferable to generate tapered gears according to this invention, by imparting the straight line motion to the tool while rotating the blank on its axis during cutting at a predetermined rate relative to this straight line motion, it is obvious that, as with other generating operations, the relative motions required may be obtained in other ways also, and it is not intended to restrict the invention to the embodiment described. So, the straight line motion might be imparted to the blank in addition to its rotary motion, in which case the tool would receive only a cutting motion, or the blank might be held stationary and all of the motion might be imparted to the tool, in which case the tool would receive in addition to its cutting motion, a motion which would be the resultant of combining the straight line motion with the rotary motion here described as preferably imparted to the blank.

The present invention may be practised in the grinding and lapping of gears and is not restricted to use only with planing or milling tools.

While I have illustrated and described certain embodiments of my invention, it will be understood that the invention is capable of further modification within its scope and the limits of the appended claims and that this application is intended to cover any variations, uses, or adaptations of my invention, following, in general, the principles of the invention and including such departures from the present disclosure as come within known or customary practice in the gear art and as may be applied to the essential features hereinbefore set forth and as fall within the limits of the accompanying claims.

Having thus described my invention, what I claim is:

1. The method of producing a tapered gear which consists in cutting its side tooth surfaces by producing a cutting motion of a tool in engagement with a tapered gear blank while rotating the blank on its axis and simultaneously producing an additional relative straight line motion between the tool and blank in a direction inclined to a generatrix

of the pitch surface of the blank to generate the tooth profiles.

2. The method of producing a tapered gear which consists in cutting its side tooth surfaces by moving a cutting edge in a curved path across the face of a tapered gear blank while rotating the blank on its axis and simultaneously producing an additional relative straight line motion between the tool and blank in a direction inclined to a generatrix of the pitch surface of the blank to generate the tooth profiles.

3. The method of producing a tapered gear which consists in cutting its side tooth surfaces by rotating a rotary annular face mill in engagement with a tapered gear blank while rotating the blank on its axis and simultaneously producing an additional relative straight line motion between the tool and blank in a direction inclined to a generatrix of the pitch surface of the blank to generate the tooth profiles.

4. The method of producing a tapered gear which consists in cutting its side tooth surfaces two sides simultaneously by producing a cutting motion of a tool, provided with cutting edges for cutting opposite side tooth faces of a blank, in engagement with a tapered gear blank while rotating the blank on its axis and simultaneously imparting an additional relative straight line motion between the tool and blank in a direction inclined to a generatrix of the pitch surface of the blank to generate the tooth profiles.

5. The method of producing a tapered gear which consists in cutting its side tooth surfaces two sides simultaneously by moving a pair of cutting edges across the face of a tapered gear blank while rotating the blank on its axis and simultaneously producing an additional relative straight line motion between the cutting edges and blank in a direction inclined to a generatrix of the pitch surface of the blank to generate the tooth profiles.

6. The method of producing a tapered gear which consists in cutting its side tooth surfaces two sides simultaneously by moving a pair of cutting edges in separate concentrically curved paths across the face of a tapered gear blank while rotating the blank on its axis and simultaneously producing an additional relative straight line motion between the cutting edges and blank in a direction inclined to a generatrix of the pitch surface of the blank to generate the tooth profiles.

7. The method of producing a tapered gear which consists in cutting its side tooth surfaces two sides simultaneously with a rotary annular face mill, having a plurality of cutting edges adapted to finish cut simultaneously adjacent side tooth faces of a gear blank, by rotating said tool in engagement with a tapered gear blank while rotating the

blank on its axis and simultaneously producing an additional relative straight line motion between the tool and blank in a direction inclined to a generatrix of the pitch surface of the blank to generate the tooth profiles.

8. The method of producing a tapered gear which consists in cutting its side tooth surfaces by producing a cutting motion of a tool in engagement with a tapered gear blank while rotating the blank on its axis and simultaneously producing an additional relative motion between the tool and blank in a straight line inclined to a plane perpendicular to the blank axis.

9. The method of producing a tapered gear which consists in cutting its side tooth surfaces by moving a tool in a curved path across the face of a tapered gear blank while rotating the blank on its axis and simultaneously producing an additional relative motion between the tool and blank in a straight line inclined to a plane perpendicular to the blank axis.

10. The method of producing a tapered gear which consists in cutting its side tooth surfaces by rotating a rotary annular face mill in engagement with a tapered gear blank while rotating the blank on its axis and simultaneously producing an additional relative motion between the tool and blank in a straight line inclined to a plane perpendicular to the blank axis.

11. The method of producing a tapered gear which consists in cutting its side tooth surfaces two sides simultaneously by producing a cutting motion of a tool, provided with cutting edges for cutting opposite side tooth faces of a gear blank, in engagement with a tapered gear blank, while rotating the blank on its axis and simultaneously producing an additional relative motion between the tool and blank in a straight line inclined to a plane perpendicular to the blank axis.

12. The method of producing a tapered gear which consists in cutting its side tooth surfaces two sides simultaneously by moving a pair of cutting edges across the face of a tapered gear blank while rotating the blank on its axis and simultaneously producing an additional relative motion between the cutting edges and blank in a straight line inclined to a plane perpendicular to the blank axis.

13. The method of producing a tapered gear which consists in moving a pair of cutting edges in separate concentrically curved paths across the face of a tapered gear blank while rotating the blank on its axis and simultaneously producing an additional relative motion between the cutting edges and blank in a straight line inclined to a plane perpendicular to the blank axis.

14. The method of producing a tapered gear which consists in cutting its side tooth

- surfaces two sides simultaneously with a rotary annular face mill, provided with a plurality of cutting edges adapted to finish cut simultaneously adjacent tooth faces of a gear blank, by rotating said tool in engagement with a tapered gear blank while rotating the blank on its axis and simultaneously producing an additional relative motion between the tool and blank in a straight line inclined to a plane perpendicular to the blank axis.
15. The method of producing a tapered gear which consists in cutting its side tooth surfaces by producing a cutting motion of a tool in engagement with a tapered gear blank while imparting a relative motion between the tool and blank corresponding to that of a cylindrical gear which is coaxial with the blank rolling on a rack which extends in a direction inclined to a plane perpendicular to the blank axis.
20. The method of producing a tapered gear which consists in cutting its side tooth surfaces by moving a tool in a curved path across the face of a tapered gear blank while imparting a relative motion between the tool and blank corresponding to that of a cylindrical gear which is coaxial with the blank rolling on a rack which extends in a direction inclined to a plane perpendicular to the blank axis.
25. The method of producing a tapered gear which consists in cutting its side tooth surfaces by rotating a rotary annular face mill in engagement with a tapered gear blank while imparting a relative motion between the tool and blank corresponding to that of a cylindrical gear which is coaxial with the blank rolling on a rack which extends in a direction inclined to a plane perpendicular to the axis of the blank.
30. The method of producing a tapered gear which consists in cutting its side tooth surfaces two sides simultaneously by producing a cutting motion of a tool, having cutting edges for finish cutting opposite side tooth faces of a blank, in engagement with a tapered gear blank, while imparting an additional relative motion between the tool and blank corresponding to that of a cylindrical gear which is coaxial with the blank rolling on a rack which extends in a direction inclined to a plane perpendicular to the blank axis.
35. The method of producing a tapered gear which consists in cutting its side tooth surfaces two sides simultaneously by moving a pair of cutting edges across the face of a tapered gear blank while imparting a relative motion between the cutting edges and blank corresponding to that of a cylindrical gear which is coaxial with the blank rolling on a rack which extends in a direction inclined to a plane perpendicular to the axis of the blank.
40. The method of producing a tapered gear which consists in cutting its side tooth surfaces two sides simultaneously by moving a pair of cutting edges in separate concentrically curved paths across the face of a tapered gear blank while imparting a relative motion between the cutting edges and blank corresponding to that of a cylindrical gear which is coaxial with the blank, rolling on a rack which extends in a direction inclined to a plane perpendicular to the blank axis.
45. The method of producing a tapered gear which consists in positioning the tool and a tapered gear blank relatively to each other so that the axis about which the tool moves coincides with the projection of the gear apex to a normal, at a mean point, to the tooth surface to be produced, and imparting a cutting movement to the tool about its axis, while producing an additional relative straight line motion between the tool and blank in the direction of said normal.
50. The method of producing a tapered gear which consists in positioning a rotary annular face mill and a tapered gear blank relatively to each other so that the center about which the tool rotates coincides with the projection of the blank apex to a normal to the tooth surface to be produced, and rotating said tool in engagement with the blank while producing an additional relative straight line motion between the tool and blank in the direction of said normal.
55. The method of producing a tapered gear which involves shaping its longitudinal tooth surfaces by movement of a cutting edge in a curved path, which consists in positioning a pair of cutting edges and a tapered gear blank relatively to each other so that the axis about which the cutting edges are to be moved coincides with the projection of the blank apex to a normal at a mean point to the tooth surfaces to be produced on the blank, and moving the cutting edges in separate curved paths across the face of the blank while producing an additional relative straight line motion between the cutting edges and blank in the direction of said normal.
60. The method of producing a tapered gear which consists in positioning a rotary annular face mill, having a plurality of cutting edges adapted to finish cut adjacent side tooth faces of a gear blank, in engagement with a tapered gear blank so that the axis about which the tool moves passes through the projection of the gear apex to a normal, at a mean point, to the tooth surface to be produced on the blank, and rotating the tool in engagement with the blank while imparting an additional relative straight line motion between the tool and blank in the direction of said normal.

ing a straight line relative movement between the tool and blank spindle in a direction inclined to a plane perpendicular to the blank axis, and means for angularly adjusting the tool support to incline the tool axis to the straight line along which the last named relative movement takes place.

36. In a machine for producing tapered gears, a tool, a blank support, a spindle adapted to carry a tapered gear blank journaled in said blank support, means for positioning the tool and blank in engagement, means for imparting a cutting motion to the tool, means for simultaneously imparting a relative movement between the tool and blank spindle corresponding to that of a cylindrical gear which is coaxial with the blank rolling on a rack which extends in a direction inclined to a plane perpendicular to the blank axis.

37. In a machine for producing tapered gears, a tool, a blank support, a spindle adapted to carry a tapered gear blank journaled in said blank support, means for positioning the tool and blank in engagement, means for moving the tool in a curved path across the face of the blank, means for simultaneously imparting an additional relative movement between the tool and blank spindle corresponding to that of a cylindrical gear, coaxial with the blank, rolling on a rack which extends in a direction inclined to a plane perpendicular to the blank axis.

38. In a machine for producing tapered gears, a tool support, a rotary annular face mill journaled therein, a blank support, a spindle adapted to carry a tapered gear blank journaled thereon, means for positioning the tool and blank in engagement, means for rotating the tool on its axis, and means for simultaneously producing an additional relative movement between the tool and blank corresponding to that of a cylindrical gear coaxial with the blank rolling on the rack which extends in the direction inclined to a plane perpendicular to the blank axis.

39. In a machine for producing tapered gears, a tool support, a tool journaled therein, a blank support, a spindle, adapted to carry a tapered gear blank, journaled thereon, means for positioning the tool and gear blank relatively to each other so that the axis about which the tool moves passes through the projection of the blank apex to a normal to a tooth side to be cut on the blank, means for moving the tool in a curved path across the face of the blank, means for rotating the blank spindle on its axis, and means for simultaneously producing a straight line relative movement between the tool and blank in a direction inclined to a plane perpendicular to the blank axis.

40. In a machine for producing tapered gears, a tool support, a rotary annular face mill journaled therein, a blank support, a

spindle, adapted to carry a tapered gear blank, journaled thereon, means for positioning the tool and blank relatively to each other so that the axis about which the tool rotates passes through the projection of the blank apex to a normal to a tooth side to be cut on the blank, means for rotating the tool on its axis, means for rotating the blank spindle on its axis, and means for simultaneously producing a straight line relative movement between the tool and blank in a direction inclined to a plane perpendicular to the blank axis.

41. In a machine for producing tapered gears, a tool support, a rotary annular face mill, provided with a plurality of cutting edges adapted to finish cut adjacent side tooth faces of a gear blank, journaled therein, a blank support, a spindle adapted to carry a tapered gear blank journaled thereon, means for positioning the tool and gear blank relatively to each other so that the axis about which the tool rotates passes through the projection of the blank apex to a normal to a tooth side to be cut on the blank, means for rotating the tool on its axis, means for rotating the blank on its axis, and means for simultaneously producing a relative straight line movement between the tool and blank in a direction inclined to a plane perpendicular to the blank axis.

42. In a machine for producing tapered gears, a blank support, a spindle adapted to carry a tapered gear blank, journaled therein, a tool support movable in a straight line inclined to a plane perpendicular to the blank spindle when the latter is in cutting position, a tool mounted on said tool support, means for imparting a cutting movement to the tool, means for simultaneously imparting a sliding movement to said tool support and means adapted to be actuated by movement of said tool support for rotating said blank spindle.

43. In a machine for producing tapered gears, a blank support, a spindle, adapted to carry a tapered gear blank, journaled in said blank support, a tool support movable in a straight line inclined to a plane perpendicular to the blank spindle when the latter is in cutting position, a tool mounted on said tool support, means for moving the tool in a curved path across the face of the gear blank, means for simultaneously imparting a sliding movement to said tool support, and means adapted to be actuated by movement of said tool support for rotating said blank spindle.

44. In a machine for producing tapered gears, a blank support, a spindle, adapted to carry a tapered gear blank, journaled therein, a tool support movable in a straight line inclined to a plane perpendicular to the blank spindle when the latter is in cutting position, an annular face mill journaled in said tool support, means for rotating said tool in engagement with the gear blank, means for

simultaneously imparting a sliding movement to said tool support, and means adapted to be actuated by movement of said tool support for rotating said blank spindle.

45. In a machine for producing tapered gears, a blank support, a spindle, adapted to carry a tapered gear blank, journaled on said blank support, a tool support movable in a straight line inclined to a plane perpendicular to the blank spindle when the latter is in cutting position, a rotary annular face mill, provided with cutting edges adapted to cut adjacent side tooth faces of a gear blank, journaled in said tool support, means for rotating said tool in engagement with the gear blank, means for simultaneously imparting movement to said tool support, and means adapted to be actuated by movement of said tool support for rotating said blank spindle.

46. The method of producing a tapered gear which consists in cutting its side tooth surfaces by producing a cutting motion of a tool in engagement with a tapered gear blank, while rotating the blank on its axis and simultaneously producing a relative straight line motion between the tool and blank in a plane tangent to a cone surface of the blank along a cone element thereof.

47. The method of producing a tapered gear which consists in cutting its side tooth surfaces by moving a tool in a curved path across the face of a tapered gear blank while rotating the blank on its axis and simultaneously producing a relative straight line motion between the tool and blank in a plane tangent to a cone surface of the blank along a cone element thereof.

48. The method of producing a tapered gear which consists in cutting its side tooth surfaces two sides simultaneously by moving a pair of cutting edges in concentrically curved paths across the face of a tapered gear blank while rotating the blank on its axis and simultaneously producing a relative straight line motion between the tool and blank in a plane tangent to a cone surface of the blank along a cone element thereof.

49. In a machine for producing tapered gears, a tool support, a tool mounted thereon, a blank support, a blank spindle journaled therein and adapted to carry a tapered gear blank, means for positioning the tool and blank in engagement, means for imparting a cutting movement to the tool, a rack member secured to said tool support, a cylindrical gear secured to said blank spindle and meshing with said rack member, and means for imparting a straight line motion to said tool support to cause the cylindrical gear to roll on the rack member.

50. In a machine for producing tapered gears, a tool support, a rotary annular face mill journaled in said tool support, a blank support, a blank spindle journaled therein and adapted to carry a tapered gear blank,

means for rotating the tool on its axis, a rack member secured to said tool support, a cylindrical gear secured to said blank spindle and meshing with said rack member and means for imparting a straight line motion to said tool support to cause said cylindrical gear to roll on said rack member.

51. The method of producing a tapered gear which consists in positioning a tool and blank in tangential relation with the axis of the blank inclined to the common tangent plane by an angle equal to the pitch cone angle of the gear to be generated, imparting a cutting movement to the tool, rotating the blank on its axis and simultaneously producing a relative straight line motion between the tool and blank in said common tangent plane.

52. The method of producing a tapered gear which consists in positioning a tool and blank in tangential relation with the axis of the blank inclined to the common tangent plane by an angle equal to the pitch cone angle of the gear to be produced, and moving the tool in a curved path across the face of the blank while simultaneously rotating the blank on its axis and producing a relative straight line motion between the tool and blank in said common tangent plane.

53. The method of producing a tapered gear which consists in positioning a rotary annular face mill and a tapered gear blank in tangential relation with the axis of the blank inclined to the common tangent plane by an angle equal to the pitch cone angle of the gear to be produced, and rotating the tool on its axis while simultaneously rotating the blank on its axis and producing a relative straight line motion between the tool and blank in said common tangent plane.

54. The method of producing a tapered gear which consists in cutting its side tooth faces two sides simultaneously by positioning a pair of cutting edges in tangential relation with a gear blank with the axis of the blank inclined to the common tangent plane by an angle equal to the pitch cone angle of the gear to be produced and moving the cutting edges simultaneously across the face of the gear blank while rotating the blank on its axis and simultaneously producing a relative straight line motion between the cutting edges and blank in said common tangent plane.

55. The method of producing a tapered gear which consists in cutting its side tooth faces two sides simultaneously with a rotary annular face mill having a plurality of cutting edges adapted to finish cut simultaneously adjacent side tooth faces of the blank, by positioning the tool and blank in tangential relation with the axis of the blank inclined to the common tangent plane by an angle equal to the pitch cone angle of the gear to be produced and rotating the tool in engagement with the blank while simultaneously rotating the blank on its axis and pro-

ducing a relative straight line motion between the tool and blank in said common tangent plane.

56. In a machine for producing tapered gears, a tool support, a tool mounted thereon, a blank support, a blank spindle journaled therein and adapted to carry a tapered gear blank, means for positioning the tool and the blank in tangential relation with the axis of the blank inclined to the common tangent plane by an angle equal to the pitch cone angle of the blank, means for imparting a cutting movement to the tool, means for rotating the blank on its axis, and means for simultaneously producing an additional relative straight line movement between the tool and blank in said common tangent plane.

57. In a machine for producing tapered gears, a tool support, a rotary annular face mill journaled in said tool support, a blank support, a blank spindle, journaled therein and adapted to carry a tapered gear blank, means for positioning the tool and the blank in tangential relation with the axis of the blank inclined to the common tangent plane by an angle equal to the pitch cone angle of the blank, means for rotating the tool on its axis, means for rotating the blank on its axis, and means for simultaneously producing an additional relative straight line motion between the tool and blank in said common tangent plane.

58. In a machine for producing tapered gears, a tool support, a tool mounted thereon, a blank support, a blank spindle journaled therein and adapted to carry a tapered gear blank, means for positioning the tool and blank in tangential relation with the axis of the blank inclined to the common tangent plane by an angle equal to the pitch cone angle of the blank, means for imparting a cutting movement to the tool, means for moving the tool support in a straight line parallel to the common tangent plane and means whereby the motion of said tool support rotates the blank spindle on its axis.

59. In a machine for producing tapered gears, a tool support, a rotary annular face mill journaled in said tool support, a blank support, a blank spindle journaled therein and adapted to carry a tapered gear blank, means for positioning the tool and blank in tangential relation with the axis of the blank inclined to the common tangent plane by an angle equal to the pitch cone angle of the blank, means for rotating the tool on its axis, means for moving the tool support in a straight line parallel to the common tangent plane and means whereby the motion of said tool support rotates the blank spindle on its axis.

60. The method of producing a tapered gear which consists in generating its side tooth surfaces by producing a cutting motion 65 of a tool in engagement with a tapered gear

blank while simultaneously effecting a relative movement between the tool and blank in the manner of a gear rolling on a rack.

61. The method of producing a tapered gear which consists in generating its side tooth surfaces by moving a cutting edge in a curved path across the face of the gear blank while simultaneously effecting a relative movement between the tool and blank in the manner of a gear rolling on a rack.

62. The method of producing a tapered gear which consists in generating its side tooth surfaces by producing a cutting motion of a tool in engagement with a tapered gear blank while simultaneously rotating the blank on its axis and imparting a relative straight-line motion between the tool and blank in a direction perpendicular to the longitudinal direction of the tooth being cut.

63. The method of producing a tapered gear which consists in generating its side tooth surfaces by moving a cutting edge in a curved path across the face of a tapered gear blank while rotating the blank on its axis and simultaneously imparting an additional relative straight-line motion between the tool and blank in a direction perpendicular to the longitudinal direction of the teeth being cut.

64. In a machine for generating tapered gears, a tool support, a tool mounted thereon, a blank support, a blank spindle journaled therein and adapted to carry a tapered gear blank, means for adjusting said supports to bring the tool and blank into tangential relation with the axis of the blank inclined to the common tangent plane, means for imparting a cutting movement to the tool, means for rotating the blank on its axis, and means for simultaneously moving one of said supports in a straight line inclined to a generatrix of the pitch surface of the blank.

65. In a machine for generating tapered gears, a tool support, a tool mounted thereon, a blank support, a blank spindle journaled therein and adapted to carry a tapered gear blank, means for adjusting said supports to bring the tool and blank into tangential relation with the axis of the blank inclined to the common tangent plane, means for moving the tool in a longitudinally curved path across the face of the blank, means for rotating the blank on its axis and means for simultaneously moving one of said supports in a straight line inclined to a generatrix of the pitch surface of the blank.

66. In a machine for generating tapered gears, a tool, a blank support, means for adjusting the tool and blank relative to each other to bring the tool and blank into tangential relation with the axis of the blank inclined to the common tangent plane, means for imparting a cutting motion to the tool, and means for simultaneously effecting a relative movement between the tool and blank

support in the manner of a gear rolling on a rack.

67. In a machine for generating tapered gears, a tool, a blank support, means for adjusting the tool and blank support to bring the tool and blank into tangential relation with the axis of the blank inclined to the common tangent plane, means for moving the tool in a longitudinally curved path across the face of the blank and means for simultaneously effecting a relative movement between the tool and blank in the manner of a gear rolling on a rack.

68. In a machine for generating tapered gears, a tool support, a tool mounted thereon, a blank support, a blank spindle journaled therein and adapted to carry a tapered gear blank, means for adjusting said supports to bring the tool and blank into tangential relation with the axis of the blank inclined to the common tangent plane, means for imparting a cutting movement to the tool, means for moving the tool support in a straight line parallel to the common tangent plane and inclined to a generatrix of the pitch surface of the blank, and means whereby the motion of said tool support rotates the blank spindle on its axis.

69. In a machine for producing tapered gears, a tool support, a tool mounted thereon, a blank support, a blank spindle journaled therein and adapted to carry a tapered gear blank, means for adjusting said supports to bring the tool and blank into tangential relation with the axis of the blank inclined to the common tangent plane, means for moving the tool in a longitudinally curved path across the face of the gear blank, means for moving the tool support in a straight line parallel to the common tangent plane and inclined to a generatrix of the pitch surface of the blank and means whereby the motion of said tool support rotates the blank spindle on its axis.
